CLAIM

The ornamental design for a valve bracket, as shown and described.

DESCRIPTION

FIG. 1 is a front perspective view of a valve bracket;

FIG. 2 is a front view of the valve bracket;

FIG. 3 is a rear view of the valve bracket;

FIG. 4 is a right side view of the valve bracket;

FIG. 5 is a left side view of the valve bracket;

FIG. 6 is a top view of the valve bracket;

FIG. 7 is a bottom view of the valve bracket; and,

FIG. 8 is a rear perspective view of the valve bracket.

The broken line showing of a valve bracket is included for the purpose of illustrating portions of the article and forms no part of the claimed design. The break lines shown in FIG. 1-3 and 6-8 are indicative of indeterminate length and form not part of the claimed design.
